UNITED STATES PATENT OFFICE.

HOWARD EARL HOOVER, OF CHICAGO, ILLINOIS, ASSIGNOR, BY MESNE ASSIGNMENTS, TO THE HOOVER COMPANY, OF NORTH CANTON, OHIO, A CORPORATION OF OHIO.

SUCTION-CLEANER ATTACHMENT.

Application filed August 16, 1920. Serial No. 403,768.

To all whom it may concern:

Be it known that I, HOWARD EARL HOOVER, a citizen of the United States, residing at Chicago, in the county of Cook and State of Illinois, have invented a certain new and useful Improvement in Suction-Cleaner Attachments, of which the following is a specification.

My invention relates to improvements in suction cleaners and more particularly to means for limiting the motion of the handle used therewith.

During the normal operation of a suction cleaner a motion is imparted to the propelling handle by the swinging of the operator's arm. It is, therefore, necessary that the handle be freely pivoted to the machine. At each end of the normal arc of travel, it is desirable that the handle become fixed relatively to the machine so that the front or rear of it can be raised by the operator when passing on to a rug, for example. In order to store the machine in a minimum amount of space, it is desirable that means be provided for locking the handle in an upright position. Under certain circumstances, the handle must be allowed to assume a position approximately parallel to the floor.

The object of my invention, therefore, is to provide a handle controlling device for suction-cleaners or the like, which will limit the free movement of the handle to the arc of travel necessary for normal operation, or allow the handle to be moved through its extreme range of travel at the option of the operator, and at the same time prevent the handle from accidental change from one range of travel to the other; and, further, to provide means whereby the handle may be locked in an upright position.

Other objects will be apparent to those skilled in the art from a study of the drawings and appended claims.

It is illustrated more or less diagrammatically in the accompanying drawings wherein:

Figure 1 is a side elevation;

Figure 2 is a partial section taken on the line 2—2 of Figure 1;

Like parts are designated by like characters throughout.

A is a suction cleaner casing with a suction nozzle A', and a discharge opening A''. B is a handle bail connected with a handle

B', being secured to it by a sleeve B''. It is pivoted on the casing by the pins B³ B³, which are secured to the bosses B⁴ B⁴ on the casing. There is a handle bail stop plate C provided with a manipulating knob or handle C'. It is pivotally mounted on one side of the handle bail at B by means of the screw C³. The plate C is provided with a slot system which consists of a short slot portion D' and a long slot portion D''. A further slot part D connects these two slot portions and at the lower end of the plate is the angle D² and the locking part of the slot system D³. This slot system could be greatly varied in size and proportions of its several parts, and the two parts of the portion D' which are here shown as at an angle to each other, might be otherwise arranged. E is a pin which is mounted on or attached to a boss E' of the casing and which projects through the slot system and is provided with a washer E² which overhangs the plate. The details of this arrangement need not be as shown. It is obvious that either the plate or the pin or projection may be mounted on the casing or on the handle bail and that either may be pivotally mounted, the object being to arrange the two parts one on the casing and the other on the handle bail in such a way that they cooperate to get the desired result.

The slot system may be greatly varied from that shown but what is important is this: that the two slot portions in which the pin travels for the two separate ranges of handle motion should be connected in such a way that the pin may pass from one to another, but that it will not tend to do so under normal conditions. The arrangement is such that gravity tends to keep the pin in whichever of these two slot portions it may happen to be traveling. As shown, gravity will tend to keep the pin in whichever of these two slot portions it may at any given moment occupy and that, during the entire movement of the handle, permissible while the pin is occupying the slot portion in question. Such an arrangement prevents accidental shifting from one range of movement to the other and compels the operator to manipulate the machine so as to bring about such shifting as and when he desires. By making the two slot portions D⁴ and D' at an angle to each other, the result is ac-

complished with the least width of plate. By putting the short slot portion under the longer slot portion, gravity tends to keep the pin or projection in its selected slot. By 5 having an extended slot part D to connect the slot portions D⁴ and D', the tendency of the pin to pass from one slot to another is reduced to a minimum. The same general result could doubtless be accomplished by 10 various modifications. When the pin is in the slot D', the handle has a free, unrestricted movement from the two extreme points of its excursion and there is no tendency of the pin to pass from this slot into 15 the short excursion slot portion D⁴ unless manipulated for that purpose by the operator.

The use and operation of my invention are as follows:

20 The position of the handle during normal operation as the machine is run back and forth will vary between that shown in full lines and that shown in dotted lines and indicated at X. This is the play which 25 the handle will make as the hand of the operator swings and rises and falls. When the machine is set away it is usually desirable to have the handle straight up as the machine will then occupy less room for 30 storage. This position is the one shown in dotted lines and indicated at Y. In order to bring the handle to that position the stop is raised so as to free the pin E from the slot portion D⁴ and allow the stop 35 plate to ride along the pin until the latter has reached the end of the slot portion D and entered the slot part D³. This is the position indicated in dotted lines at Y.

In order to allow the machine to be run 40 under low articles of furniture and the like it is necessary to place the handle in the position shown in dotted lines Z. The manner of doing this is similar to the manner of raising the handle to the vertical position 45 only that instead of allowing the stop plate to come to rest with the pin in the end of the slot at D³, the stop plate is so manipulated as to allow it to slide about the pin and to bring the pin into the portion D'.

When it is desired to use the machine the 50 relation of parts is that shown in full lines. In that position the stop will normally slide on the pin which will lie within the short 55 slot portion D⁴. This arrangement cannot accidentally be displaced. In order to move the handle to the vertical or to the horizontal position it is necessary to positively manipulate the stop.

60 I claim—

1. In a suction cleaner comprising a casing having a pivoted handle, the handle including a pivotally mounted member provided with a slot system the upper edges of 65 which are uninterrupted and act as guide-

ways, which system comprises a short slot, a long slot, and a connecting slot extending from the long slot to the underside of the short slot, and a member adapted to be received in said slot system, one member being 70 mounted on said handle, the other member being mounted on said casing.

2. In a structure having a pivoted handle, a controlling device for the handle comprising a member provided with a system of connected slots, and a second member adapted to project through said slots, said slots being provided with uninterrupted upper surfaces acting as guideways, one of said members being mounted on the handle and one 80 of said members being pivotally mounted on a separate portion of the structure.

3. In combination with a tool and a handle pivotally mounted thereon, a controlling device comprising a pivotally mounted member and a fixed member, one of said members being mounted on the handle and the other on the tool, one of said members being provided with a series of connected slots each having an uninterrupted edge, tending 90 throughout the range of travel to contact with the other member under the influence of gravity and acting as a guideway.

4. The combination with a tool and a pivoted handle bail therefor, of means for limiting the motion of the handle bail at its upper and its lower positions and for limiting its excursion to a relatively narrow arc of movement intermediate such positions, said means comprising two engaging members, one mounted on the tool, the other on the handle bail, and one being pivotally mounted, one of said members being provided with a slot system comprising two portions having uninterrupted upper surfaces 100 with which the other member contacts throughout the range of travel and under the influence of gravity and which act as guideways, and a third portion connecting them.

5. The combination with a tool and a pivoted handle bail therefor, of means for limiting the motion of the handle bail at its upper and at its lower positions and for limiting its excursion to a relatively narrow 110 arc of movement intermediate such positions, said means comprising two co-operating members, one mounted on the tool, the other on the handle bail, and one being pivotally mounted, one of said members being provided with a slot system comprising two portions having uninterrupted upper surfaces with which the other member contacts throughout the range of travel under the influence of gravity and which act as guideways, connected by a third portion and having a locking part adapted to hold the handle bail in an upright position.

6. In combination with a tool and a handle pivotally mounted thereon, a controlling de- 120

- vice comprising inter-engaging pivotally mounted and fixed members, one of said members being mounted on the handle and the other on the tool, one of said members being provided with uninterrupted guide edges formed by the edges of guideways provided in it which tend to contact throughout the range of travel with the other member under the influence of gravity, the whole 10 acting as a guideway system for the handle, each of the guide edges being provided with a stop at each end.
7. A handle bail stop comprising a pin and a plate, one of them pivotally mounted, a guideway system in the plate adapted to be engaged by the pin, the guideway system comprising two separated guides, each of them terminating at each end in a stop, the guides being of unequal length, a connection 20 between said guides, the pin and guideway system being adapted to be held in working relation by gravity, the pin being adapted to be shunted from one guide to the other only by manual rotation of the pivoted 25 member to permit passage of the pin through the connection.
8. In combination with a tool and a handle pivotally mounted thereon, a handle con-
- trol comprising a guide member and a guided member, one mounted on the handle, the other mounted on the tool, one of said members having a guideway system therein adapted to be engaged by the other member, the guideway system comprising two separated guides, each of them terminating at each end in a stop, one guide and stop group being adapted to limit the movement of the guided member between widely separated points and the other adapted to limit the movement of the guided member between 30 less widely separated points, the end of one guide extending beyond the end of the other guide, a connection between these ends of said guides, the members being adapted to be held in working relation by gravity, one 35 of the members being adapted to be shunted from one guide to the other through the connection only by manual rotation of one of the members.
- In testimony whereof, I affix my signature in the presence of two witnesses this 12 day of August 1920.

HOWARD EARL HOOVER.
